UNITED STATES PATENT OFFICE.

RODNEY J. WOOD, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CREDIT FILE.

Application filed January 12, 1923. Serial No. 612,181.

This invention relates generally to filing systems, and has particular reference to filing cabinets for filing memoranda regarding transactions with customers in retail stores.

5 One object of the invention is to provide a protected filing cabinet which will be a safe and convenient place for the filing of customers' account books.

Another object of the invention is to provide 10 customers' account book receptacles which are cheaply constructed, compact and efficient, and which produce a filing cabinet that is economical from a manufacturing standpoint.

15 Another object is to provide in addition to account book files, a plurality of sales slip files for temporary customers' accounts.

With these and incidental objects in view, the invention consists of certain novel features of construction and combinations of parts, the essential elements of which are set forth in appended claims and a preferred form or embodiment of which is hereinafter described with reference to the drawings 25 which accompany and form part of this specification.

Of said drawings:

Fig. 1 is a right side elevation of the filing device with the right hand side of the housing omitted.

30 Fig. 2 is a detail view of a sales book container.

Fig. 3 is a section taken on the line 3—3 of Fig. 1, showing the cover of a sales book, partly broken away.

35 Fig. 4 is a sectional view taken on the line 4—4 of Fig. 1.

The improved device comprises a number of receptacles adapted to receive sales books 40 used in retail stores for customers' charge accounts, and also a number of pivoted units or sections provided with holders to receive temporary accounts or memoranda.

The sales book receptacles are arranged on 45 a slight incline so as to have the names on the various sales books clearly visible and to provide easy access to the books.

The pivoted units comprise a plurality of leaves which are adapted to receive sales slips 50 and are arranged horizontally so that they slightly overlap each other to enable the operator to see the index card placed in the upper right hand corner of each leaf.

Describing the device in detail, the filing

units are enclosed in a casing or housing 15 55 constructed of double walls packed with a suitable fire resisting material. The casing includes a top lid 16 (Fig.1) consisting of two sections hinged together at 17. The rear-most section is hinged to the rear wall of 60 the casing by a hinge 18. The casing also includes a front lid consisting of two sections 19 and 20, hinged together at 21, the lower-most section being connected to the bottom of the casing by a hinge 22. The hinges may be 65 of any suitable construction. The front lid 19 is equipped with a latch member 23 of any preferred form for connecting the lids 19 and 16.

The top lid 16 is opened by folding the sections thereof and swinging the same upwardly and over toward the rear wall of the casing. A rubber bumper 24 secured in the back of the casing, prevents the lid from being swung into contact with the casing and thereby protects the finish of the casing. 75

Secured on the inside of each side wall 70 and lengthwise of the casing are brackets 28 and 29 which support sales book receptacles 30 and extend at an incline from front to rear 80 of the casing. Near the top of the casing and parallel with brackets 28 and 29 are two similarly inclined strips 31 and 32, each provided with a base secured to the side walls 70 of the casing and an offset 71 spaced from the casing to form a groove in connection therewith to receive extensions 72 on the end walls 73 of the receptacles 30, as shown in Figs. 1 and 3. These receptacles are open on the front and top, as shown in Fig. 2, and when in position, the back of one receptacle serves as a front or cover for the receptacle behind it. The extensions 72 are shaped as shown in Fig. 1 to provide an effective interlocking engagement with the strips 31 and 32 against shifting from side to side of the casing 15 or vertically thereof. 90

A back stop 33 (Fig. 1) with formed ends 34 and 35, extends across the casing and is secured to the side members 70 of the casing, 100 to form an abutment at the rear end of the casing for the receptacles 30. This back stop is placed on a slight angle to support the series of receptacles at a slight backward incline and hence afford easier access to the sales 105 books 36 contained in the receptacles.

After the sales book receptacles have been positioned within the casing, as shown in

Fig. 1, they are secured in place against rocking by a retaining receptacle 37 which is of the same form as the receptacles 30. This retaining receptacle 37 is made rigid by means of a brace plate 38 which extends across the front of the retaining receptacle, with its opposite ends formed at right angles and secured to the sides of the retaining receptacle. Elongated openings 39 are provided in each side of the retaining receptacle 37 through which screws 40 pass to secure the retaining receptacle to the side walls of the casing. The side walls of the casing are reinforced at these points by plates 41 and 42 to give sufficient thickness of metal for the screws.

The receptacles 30 can be made of different widths to accommodate any number of sales books of various sizes. The receptacles shown in Fig. 3 each contain four sales books.

20. In addition to a plurality of sales book receptacles, there are provided two horizontally pivoted supporting units or sections 46 and 47 having a plurality of vertically pivoted overlapping leaves 48 adapted to receive sales slips or memoranda 49 between them. These supporting units are pivoted at their lower ends by means of lugs 50 and 51 engaging holes in brackets 52 and 53 secured to the base of the casing. The brace plate 38 of the stationary retaining receptacle 37 serves as a back rest for the rearmost pivoted unit 47. A ledge 54 formed on the lower edge of each of the supporting units provides a support for the sales slips or memoranda 49 and prevents them from working down out of proper position. At their sides, the supporting units carry forwardly projecting brackets 55 of sufficient length to space the units apart and prevent one unit from disturbing the slips filed in another when the supporting units 46 and 47 are rocked. In normal position, the supporting units are slightly inclined toward the rear of the machine with the upper portion of the rearmost unit 47 supported by the retaining receptacle 37.

The leaves 48 are hinged at their left hand edges to their respective supporting units by hinge pins 57 (Fig. 4). Springs 56 encircling the hinge pins 57, tend at all times to swing the leaves toward the unit. At their upper ends, the leaves have struck forward from their material, flanged lips 58 suitably formed to receive cards 59 bearing identification data. The first leaf on the left hand side is partially covered by a flash member 60 which is similar in construction to that of the leaves.

Placed in front of the foremost unit 46, 60 and pivoted in the same manner as the unit, is a plate 65 which, when the lids 19 and 20 are lowered, can be swung forward until one

or more arresting angle members 66 secured thereon, engage the base of the casing. When this plate 65 is in its forward position, 65 easy access is had to the unit files 46 and 47. In use, the filing receptacles 30 remain in their positions shown in Fig 1 without rocking, being held against movement by the retaining receptacle 37.

70 While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

75 What is claimed is:

1. In a filing device, a casing, filing receptacles having side walls, projections on said side walls, means for supporting said receptacles within said casing, and members having off-set portions secured to said casing walls and forming with said walls grooves 85 for receiving said projections for retaining said receptacles in position on said supporting means.

2. In a filing cabinet, a casing, filing receptacles having side walls terminating in 90 projections, said projections being higher than the receptacles, supporting means for the receptacles, and members secured to the casing walls adapted to cooperate with said projections for holding said receptacles in 95 position.

3. In a filing cabinet, a casing, a plurality of receptacles having side walls terminating in projections, said projections being higher than the receptacles, a bar adapted to cooperate with said projections for holding said receptacles against vertical displacement, and a single receptacle adjustably mounted in said casing for preventing longitudinal displacement of all of said receptacles. 100

4. In a filing cabinet, the combination with a casing; and a row of individual and separate filing receptacles arranged in a row freely within the casing; a support against which rests the rearmost filing receptacle of the row; and stationary means on which rests the row of filing receptacles, to support the receptacles at an incline within the casing; of means extending along the walls of the casing to prevent sidewise as well as vertical movement of the series of filing receptacles; and means to adjustably secure the foremost receptacle of the row to the walls of the casing to serve as a locking means to retain all of the freely mounted receptacles in their assembled positions fixedly against rocking movement from front to back. 110

115 In testimony whereof I affix my signature.
RODNEY J. WOOD.
